TIRE ALARM SIGNAL STATION

Morris Levy, Philadelphia, Pa.

Application May 13, 1952, Serial No. 287,640

2 Claims. (Cl. 200—142)

1

My invention relates to a new and useful fire alarm signal station and, broadly, the object thereof is to produce a signal station including an electric switch normally retained in an open condition and capable of being released by manual action or due to the presence of abnormal heat in the vicinity of the signal station to cause an alarm to be sounded.

One specific object of the present invention is to produce a fire alarm signal station in which means is provided to normally retain the switch closed, said means being ordinarily maintained in a switch holding position by a fusible element that may be manually disengaged from its anchorage or melted by abnormal heat to release the switch whereby said switch can close to cause a warning signal.

Another object of the invention is to provide a fire alarm signal station including a switch normally maintained in an open position by a frangible panel which may be broken by a spring actuated hammer directly or indirectly held in a neutral or "cocked" position by a fusible element, said hammer being releasable manually or when the fusible element melts due to the presence of abnormal heat.

Another object of the invention is to provide a spring actuated swinging hammer normally maintained in the neutral position by a fusible link which when manually detached or melted by abnormal heat will release the hammer to break the panel whereby the switch may be closed.

Another object of the invention is to provide a spring actuated hammer projectable in a straight line and controlled by a spring operated bar which, in turn, is maintained in a retracted position by a fusible link that when manually detached or melted by abnormal heat will liberate the bar to release the hammer for breaking the panel to allow the switch to close.

A further object of this invention is to incorporate a fusible element in the frangible panel whereby the switch may be released upon the melting of said fusible element or the breaking of the panel by a separate instrument wielded from the outside of the signal station.

A still further object of the present invention is to provide a fire alarm signal station including a switch normally maintained in an open position by a frangible and fusible panel which when broken or melted will release the switch to permit it to close.

With the above and other objects in view this invention consists of the details of construction and combination of elements hereinafter set forth and then designated by the claims.

2

In order that those skilled in the art to which this invention appertains may understand how to make and use the same I will describe its construction in detail referring by numerals to the accompanying drawing forming a part hereof, in which:

Fig. 1 is a perspective view of a fire alarm signal station including a slidably mounted reciprocating bar for controlling the switch, portions being broken away to illustrate details of construction and showing in dotted lines a number of positions the bar may assume for releasing the spring.

Fig. 2 is a section on the line 2—2 of Fig. 1.

Fig. 3 is a perspective view of a signal station having a spring actuated swinging hammer for breaking a frangible panel.

Fig. 4 is a fragmentary perspective view of a modification.

Fig. 5 is a section on the line 5—5 of Fig. 4. Fig. 6 is a sectional view of another type of alarm station illustrating a fusible element incorporated in the frangible panel.

Fig. 7 is a similar view of a further modification utilizing a frangible and fusible panel showing it in condition to normally retain the switch in open position.

Fig. 8 is a like view of the same station upon the melting of a portion of the panel.

In carrying out my invention as herein embodied, particular attention being first directed to Figs. 1 and 2, the numeral 10 denotes the body and 11 is the cover of a casing of a fire alarm signal station, said cover being attached to the body by screws 12 or equivalent fastening means.

The body is to hold an electric switch and for this purpose I have shown a chamber 13 in which is mounted the terminal member 14 and the stationary contact 15 each of which is to be connected with one side of an electric circuit including an alarm device (not shown). Attached to said terminal member is a movable spring contact 16, the free end of which underlies the stationary contact reciprocatingly mounted in a recess 17 in the bottom of the chamber. Said movable contact is fashioned to provide an outwardly projecting knee 18 for a purpose to be presently described.

A switch controlling bar 19 is slidably mounted longitudinally in a slot 20, Fig. 2, in the casing and the movements thereof limited by the length of a slot 21 in the rear end of the bar through which slot is projected a fastener 22 into a suitable part of the casing, as the body thereof. The bar lies across the open end or top of the chamber in line with the movable contact to engage the knee of said movable contact for depressing the latter

under certain conditions, fully set forth below, and the forward end of said bar protrudes outside of the casing and may be provided with a handle 23.

An aperture 24 is formed in the switch control bar 19 between the ends thereof to receive the knee 18 of the movable contact when the bar 19 is in a retracted position merely to prevent said movable contact from slipping sidewise when the latter is retracted. Also formed in said bar 19 to the rear of the aperture 24 is an opening 25 of sufficient size to allow the knee 18 of the movable contact to project therein an appropriate distance to cause said movable contact to engage the stationary contact and close the switch while the bar is depressed but pulled outwardly longitudinally of itself.

The control bar is held in a depressed position, as shown by full lines in Figs. 1 and 2, by a fusible element 26 of any appropriate construction but which, for purposes of illustration, is shown as comprised of two plates 27, 28 joined by a solder having a fairly low melting point. The fusible element 26 has a slot 29 through which the bar 19 projects for slidably mounting the latter relative to the fusible element which is normally anchored to the casing by fastening means 30, such as a screw.

In a case of fire while no one is present, the abnormal heat generated will melt the fusible element 26 and liberate the control bar 19 thereby releasing the movable spring contact 16 which is sufficiently strong to lift the bar 19 in the casing slot 20 as shown at 19a, to permit said movable contact to engage the stationary contact 15 and thereby close the switch in the station for causing an alarm. On the other hand if someone is present and can reach the station before it is automatically actuated, the bar 19 can be pulled outwardly longitudinally of itself, as indicated at 19b. This will position the aperture 25 into alignment with the knee 18 of the movable spring contact 16 at which time said knee may pass through the aperture a sufficient distance to cause the movable contact to engage the stationary contact for closing the switch to produce an alarm.

In Fig. 3 the casing or body 31 has a chamber 32 covered by a frangible panel 33 held in place by fastening devices 34, such as screws. Within the chamber 32 is mounted a switch the same as that previously described and including the terminal member 14 and the stationary contact 15. The movable spring contact 16 is attached at one end to the terminal member and has its free end underlying the stationary contact and reciprocatingly mounted in the recess 17 in the bottom of the chamber 32. The movable contact 16 is fashioned to provide a knee 18 which the panel 33 engages to depress the movable spring contact 16 and normally hold it out of engagement with its companion stationary contact 15 whereby the switch is normally open until the panel 33 is broken.

To break the panel 33 a spring operated hammer is provided which includes a head 35 mounted on a shank 36 having a right angled journal 37 mounted in bearings 38. A coil spring 39 surrounds the journal 37 and has one end fixed to the body or casing and the other end attached to the hammer in a manner to urge the head towards the panel 33 in the arc of a circle so as to strike and break said panel. The hammer is ordinarily retained in a retracted position, as shown by full lines, by the fusible ele-

ment 40 having one end connected to said hammer and the other end temporarily attached to the body or casing by a detachable fastening device 41, such as a screw or headed pin.

In operation, when the heat is due to a fire in the vicinity of the station the fusible element 40 will melt and release the hammer which then will be propelled by the spring 39 until said hammer hits and breaks the panel. This will release the movable spring contact of the switch whereby said movable contact will engage the stationary contact to close the switch for causing an alarm. If the fire is not close enough to melt the fusible link and a person is present the fastening device 41 can be manually withdrawn and the same purpose accomplished.

The station shown in Figs. 4 and 5 comprises the body or casing 42 having the usual switch holding chamber 43 across the open end of which is disposed the frangible panel 44. In back of the casing 42 in alignment with the chamber is a recess 45 to provide a partition 46 and offset from said chamber is a compartment 47 communicating with the chamber through a channel 47a.

In the chamber 43 is mounted the usual switch including the terminal member 14, the stationary contact 15, the movable spring contact 16 having one end attached to the terminal member and the other or free end underlying the stationary contact and reciprocatingly received in the recess 17, said movable contact being provided with an outwardly projecting knee 18 coacting with the panel whereby, when the latter is fixed in place, the movable spring contact is depressed to retain the switch in an open condition.

A longitudinally propelled hammer 48 is supported by the partition 46 underneath of and substantially at right angles to the panel 44 and is urged towards the same by a spring 49. The hammer is normally retained in a retracted position by a control bar 50 which, for purposes of illustration, is shown as having a slot 51 opening into a hole 52 large enough for the passage of the hammer which has a reduced neck 53 to be received in the slot 51. The control bar is urged rearwardly or retracted by a spring 54, the tension of which can be adjusted by a screw 55, and said bar is moved forwardly by a pull rod 56 which is a part of said bar although said parts may actually be separate pieces as shown. The pull rod also has a reduced neck 57 providing a circumferential groove in which the fusible element 58 is received, the latter having an open ended slot 59 whereby said fusible element may be detachably mounted on the pull rod neck.

The operation of the type of station shown in Figs. 4 and 5 is as follows: When the fusible element 58 is melted by abnormal heat or said fusible element manually removed from the pull rod 56 the control rod 48 will be retracted by its spring 54 until the hole 52 in said rod 48 is aligned with the hammer 48 thereby liberating the latter so that it can be propelled forwardly by its spring 49. The hammer will break the panel and release the movable spring contact 16 whereupon it will engage the stationary contact to close the switch and produce an alarm. To reset the station, the hammer is pushed back, the control rod pulled forwardly and the fusible element replaced on the pull rod, if said fusible element had been removed intact; or a new one substituted if the former one had been melted. Finally a new panel 44 is substituted for the

broken one and secured in place to depress the movable spring contact and thereby open the switch.

The station shown in Fig. 6 includes a casing 60 having the customary switch holding chamber 61 across the open end of which is disposed the usual frangible panel 62 which, in this instance, has a fusible element 63 in the form of a plug or equivalent structure fixed in a hole 64 in said panel. Within the chamber 61 is mounted the usual switch including the terminal member 14, the stationary contact 15, the movable spring contact 16 having one end attached to the terminal member and the other or free end underlying the stationary contact and reciprocatingly received in the recess 17, said movable spring contact being provided with an outwardly projecting knee 18 coacting with the panel through the medium of the fusible element which it directly engages. The fusible element 63 projects into the switch chamber 61 a sufficient distance to depress the movable contact out of engagement with the stationary contact to normally maintain the switch in an open condition but when the fusible element is melted there is sufficient space provided to allow said movable contact to spring outwardly and engage the stationary contact.

In operation, any abnormal heat caused by a fire in the vicinity of the station will melt the fusible element 63 and release the movable contact whereby the switch will be closed and an alarm sounded. To actuate the device manually the panel is broken by a hammer provided for this purpose or any convenient instrument can be used. To reset the device a new panel with the fusible element thereon is put in position to replace the damaged or destroyed one.

The modification illustrated in Figs. 7 and 8 comprises an appropriate casing 65 having the usual switch holding chamber 66 across the open end of which is disposed a frangible and fusible panel 67. In the chamber 66 is mounted the usual switch including the terminal member 14, the stationary contact 15, the movable spring contact 16 having one end attached to the terminal member and the other or free end underlying the stationary contact and reciprocatingly received in the recess 17, said movable spring contact being provided with an outwardly projecting knee 18 coacting with the panel 67.

The movable spring contact 16 is normally depressed by the panel so that the switch is open, as shown in Fig. 7. If the panel is broken by the use of an outside instrument or a fire reaches the station to melt or soften said panel the movable spring contact will deform or push a hole 55 68, Fig. 8, in said panel to permit said movable

contact to move outwardly a sufficient distance for it to engage the stationary contact and close the switch, as depicted in said Fig. 8, whereby an alarm will be sounded.

5 From the foregoing it will be apparent that I have produced a fire alarm signal station in which the switch is directly controlled by means to be liberated either manually or automatically for releasing said switch to cause the sounding of an alarm.

10 Of course I do not wish to be limited to the exact details of construction herein shown and described as these may be varied within the scope of the appended claims without departing from 15 the spirit of my invention.

Having described my invention what I claim as new and useful is:

1. A fire alarm signal station comprising a casing body having a chamber open at the front, a cover mounted on said body to close the chamber and provided with a slot in communication with said chamber and opening through an end of the cover to the exterior of the latter, an electric switch located in said chamber and including a movable contact constantly urged towards the open front of the chamber and having a knee projecting outside of the chamber and into the cover slot whereby the switch is closed, a control bar mounted on the body and reciprocal to and 20 from relative to the chamber and slidably longitudinally within the slot and protruding therefrom said bar coacting with and normally depressing the movable contact to retain the switch in open condition and said bar having a hole 25 through which the knee of the movable contact may pass when said hole is aligned therewith, and a fusible element attached to the casing body and slidably receiving the protruding end of the control bar whereby the melting of said fusible element or the pulling of said bar to align the hole with the knee of the movable contact will release the latter to close the switch.

2. The structure according to claim 1 wherein the control bar has an aperture for registration with the knee of the movable contact to hold the latter in a centered position while the same is depressed.
